(57) **CLAIM**

The ornamental design for a dimmer switch plate, as shown and described.

DESCRIPTION

FIG. 1 is a perspective view of a dimmer switch plate showing our new design;

FIG. 2 is a first end view thereof, the opposite end being a mirror image of the end shown;

FIG. 3 is a front elevational view thereof; and,

FIG. 4 is a first side view thereof, the opposite side being a mirror image of the side shown.
